UNITED STATES PATENT OFFICE.

ANDRÉ RIVET, DECEASED, LATE OF PARIS, FRANCE, BY HENRI RIVET, LEGAL REPRESENTATIVE, OF PARIS, FRANCE; SAID HENRI RIVET, HEIR, ASSIGNOR TO GENERAL ELECTRIC COMPANY, A CORPORATION OF NEW YORK.

CIRCUITS FOR SPACE-CURRENT DEVICES.

Application filed July 3, 1924, Serial No. 724,146, and in France July 5, 1923.

This invention relates to improvements in circuits for space current devices.

The purpose of the invention is to provide a circuit in which three electrode space current devices may be operated by alternating current.

It is well known that when direct current is used for operating a three electrode space current device having interconnecting apparatus associated in circuit relation therewith the result is that the difference in potential between the extreme ends of the filament is equal to the voltage impressed upon said filament. When direct current is used the difference in potential does not interfere with the efficiency of the device, but in the case of alternating current the variations in potential difference between the grid and filament and particularly the variations in the plate current interfere with reception and hence are objectionable. It is one of the objects of the invention to arrange the circuit of the space current device in such manner that such current variations are obviated or at least reduced to a minimum when alternating current is used for heating the filament.

A further object of the invention is to devise a circuit in which ordinary industrial alternating current sources may be used without the danger of introducing into the circuit disturbances such as the well-known "alternating current hum."

The theory of the invention and its application to the circuits of space current devices will be readily understood by reference to the following specification taken in conjunction with the accompanying drawing while the scope of the invention will be set forth in the appended claims.

Referring to the drawings, Figure 1 illustrates a conventional detector circuit adapted for alternating current operation. Figure 2 designates a single stage amplifier also adapted for alternating current operation and in which the grid and plate are connected directly to points on the filament.

In considering the ordinary single stage amplifier circuit comprising an input circuit, an output circuit and sources of direct current for operating the filament, plate and grid it is assumed that suitable excitation and output transformers are associated with the

three electrode space current device and that the most satisfactory region of the characteristic in which said space current device operates is governed by the grid voltage supplied by a direct current source.

In operating such an amplifier circuit with alternating current, as indicated in Figure 2 assume that the grid and plate are connected directly to points located between A and B on the filament and that the center O of said filament is taken as the zero of the potentials, N representing the point of attachment of the grid and M that of the plate. The filament A B is heated by an alternating current source having a voltage represented by

$$U = U_m \sin \omega t$$

U_m being the maximum pressure. By connecting a potentiometer A' B' to the terminals of the filament, either the grid or the plate may be connected to an equipotential point of any part of the filament.

If, now, the grid be connected to any point N on the filament or of its equivalent on the potentiometer N', and if the plate be connected to any other point M or M', a variable plate current will be set up in addition to the direct current.

If the points M and N are properly located on the potentiometer, the plate current will be quite constant. Equilibrium conditions may be attained by arbitrarily selecting the position of either point, say M, and then manipulating the position of its counterpart N upon the potentiometer until optimum circuit conditions are secured.

If the plate is connected to any point M then the location of the point N on the filament may be determined by the following calculation: let 1 be the distance ON, λ the distance OM and 2L the length of the filament which is assumed to be homogeneous.

At any moment t , the voltage at the terminals of the filament AB is $U_m \sin \omega t$; the alternating grid voltage is $1/2$ of U_m

$$\sin \omega t \left(\frac{1}{L} \right) \text{ and that of the plate } 1/2 U_m \sin \omega t \left(\frac{\lambda}{L} \right)$$

Let Z be the total impedance of the plate circuit, K the amplification coefficient of the space current device in volts and $I_m \sin \omega t$

$(\omega t - \phi)$ the alternating plate current. Then ϕ represents the displacement of the plate current with respect to the voltage U .

The following relation will then exist between the alternating plate current and the variations in grid and plate voltage

$$\frac{1}{2}U = m \sin \omega t \left(\frac{K}{L} \frac{1+\lambda}{L} \right)$$

in which I_m will be zero whatever may be the value of t if the second member of the equation is zero, that is to say if

$$\frac{K}{L} + \frac{\lambda}{L} = 0$$

or

$$K_1 = -\lambda$$

or

$$-\frac{\lambda}{1} = K$$

Upon adjusting the signs of λ and L the negative prefix indicates that M and N should be located each to one side of O .

On the other hand, for any point M which defines a definite value of λ there will exist one position of N giving a zero plate current, determined by the relation

$$-\frac{\lambda}{L} = K$$

inasmuch as K is assumed to be positive and greater than unity.

The two special cases which occur most frequently in actual practice are

1. $\lambda = L$ where $1 = \frac{L}{K}$ the plate being connected to one of the ends of the filament.

2. $\lambda = 0$ where $1 = 0$ the points of attachment of the grid and plate being connected together at point O .

It is not essential that the plate be connected to the exact middle point of the filament or even to an equipotential point.

45 This point may be any one, but once chosen the position of the point of attachment of the grid is governed by this choice. Upon the proper determination of this point depends the successful alternating current operation of a three electrode space current device.

Figure 1 shows an arrangement of a detector circuit adapted for alternating current operation. The voltage of the source P_3 must be chosen so that the grid potential causes the valve to operate on an elbow or kink of the plate characteristic which is, however, sufficiently large to permit slight variation of the K of the space current device.

Alternating current may also be used for operating a plurality of three electrode space current devices connected in cascade in accordance with the principles set forth above for single stage work. It is to be

understood, of course, that there must be provided for each device a feed transformer and potentiometer. Separate sources of grid and plate voltage may be provided or common sources may be used if all of the space current devices have the same amplifying coefficient.

In actual practice the amplifying coefficient may vary slightly from one space current device to another and thus produce a slight noise in the receiving set. Although in some cases this may not be objectionable, it may become intolerable when sufficiently amplified.

The difficulty may be obviated by so arranging and adjusting the connecting apparatus, transformer, or the like between two consecutive three electrode space current devices in an amplifying circuit operating at say a frequency F that its output is the maximum at that frequency. When alternating current is used for heating the filament the connecting apparatus must then be so arranged and adjusted that the output is very small with respect to the frequency of the feeding current and its harmonics, particularly the second harmonic, as compared with the output at the frequency to be amplified. Under these conditions any noise caused by the heating current of a given space current device is transmitted but slightly or else not at all to the next succeeding device thus permitting quiet amplification.

In the case of high frequency amplification the above described results may readily be obtained but strict adherence to these conditions is especially necessary in connection with audio frequency amplification. In this case the circuits must be designed to lower the output of the apparatus when commercial frequencies are used without appreciably decreasing their audio frequency output. This may be accomplished for example by placing an air gap in the magnetic circuit of the connecting transformer, inserting resonant shunt circuits or inserting one or more artificial lines between the space current devices or after the last amplifier. In the preferred form of the invention the grid and the plate are connected to suitable points of a potentiometer connected to the terminals of the filament, but the arrangement is not limited to the use of a potentiometer and may be varied without departing from the scope of the invention for example by connecting the grid and the plate to suitable points of the winding of the supply transformers.

What is claimed as new and desired to be secured by Letters Patent of the United States, is,—

1. The combination with an electrical discharge device having a cathode adapted to be heated, a cooperating anode and a discharge controlling grid, of a source of alter-

nating current applied to said cathode for heating purposes, external circuit connections between said cathode and anode and between said cathode and grid, and means 5 for independently adjusting the connections of the anode and grid to the cathode in such a way that variations in anode potential due to the heating current of the cathode may be compensated for by variations in 10 the grid potential produced by the source of heating current.

2. The combination with an electrical discharge device having a cathode adapted to be heated, a cooperating anode and a discharge controlling grid, of a source of alternating current applied to said cathode for heating purposes, a potentiometer in shunt with said cathode, external circuit connections between said cathode and anode and between said cathode and grid, and means 15

for independently adjusting the connections of the anode and grid to the cathode through said potentiometer to compensate for the variations in anode potential caused by the heating current of the cathode. 25

3. The method of eliminating the alternating current hum from the output circuit of a space discharge device provided with a cathode connected to alternating current terminals in shunt to a potentiometer and with 30 a grid and anode connected to said potentiometer through different terminals, which comprises adjusting one of said terminals, and independently adjusting the other of said terminals. 35

In witness whereof, I have hereunto set my hand this 23d day of June, 1924.
